UNITED STATES PATENT OFFICE.

BESHARA I. MALOUF, OF SALT LAKE CITY, UTAH.

PORTABLE VULCANIZER.

1,269,629.

Specification of Letters Patent. Patented June 18, 1918.

Application filed December 27, 1916. Serial No. 139,135.

To all whom it may concern:

Be it known that I, BESHARA I. MALOUF, a citizen of the United States, residing at Salt Lake City, in the county of Salt Lake and State of Utah, have invented certain new and useful Improvements in Portable Vulcanizers, of which the following is a specification.

The present invention relates to improvements in vulcanizing devices and in particular to the portable type constituting a handy repair kit by means of which punctures in inner pneumatic tubes for vehicle tires may be readily and quickly mended.

15 The invention comprises essentially a fuel holding element consisting of a metallic pan carrying at one side a vulcanizable substance or "patch" and at the other side a heat supplying substance and a clamping means for holding said element in position upon the tube to be repaired.

I am aware that devices of this general type have been proposed heretofore and it is with a view of overcoming certain disadvantages which arise in the use of these that my invention has been evolved. For example, some difficulty is experienced in the manipulation of vulcanizers of this construction in obtaining and maintaining proper disposition of the vulcanizable material or the member carrying the same while the clamping instrumentality is arranged in operative relation to hold said material exactly over the desired point of the puncture. This is eliminated in my device by reason of the fact that the patch carrying element is removably held by the clamping member so that in operating the latter the patch is easily disposed where desired. Again, in performing 30 vulcanizing processes of this character it is very desirable to apply whatever heat is required only where it is needed; in other words, the cured material of the vehicle tube should not be unnecessarily subjected to heat as the tendency is under such condition to 45 destroy the "life" of the rubber.

Now, punctures in pneumatic tires are either small minute openings, or where more serious they are of elongated form, slits, and 50 these generally follow the grain of the rub-

ber tube so that they are found to occur transversely at times, longitudinally or diagonally with respect to the tube at other times. Therefore, it has been my aim to arrange in my device for the use of a patch 55 of the desired elongated form and to provide clamping means with pressure elements which coöperate with the fuel holding means so mounted that said holding means may easily be shifted to the proper angle and 60 over the opening of the tube. On the other hand if the holding means for the inflammable material is of circular or other form than the elongated, so as to be of sufficient size to take care of the vulcanization of a 65 rupture of greater or less serious character, or, if said holding means is stationary, the very disadvantage above referred to, of subjecting portions of the tube surrounding the puncture to unnecessary heat results. 70

For a full understanding of the present invention, reference is to be had to the following description, and the accompanying drawing, in which:

Figure 1 is a side elevation of a device constructed in accordance with my invention. 75

Fig. 2 is a top plan view thereof.

Fig. 3 is a bottom plan of the overhanging arm with the fuel holding means in position upon the pressure device, carried by said 80 arm.

Referring to the drawing, the vulcanizing device consists of a base 1 preferably of circular configuration and of a suitable size to support a portion of a rubber tube, as indicated at 2 when performing the vulcanizing process upon the same. At one side the base is provided with an extension 3 to which is pivotally connected at 4 an overhanging arm 5 terminating at its extremity in a slot 6 extending longitudinally. Diametrically opposite to the extension 3 is a forked extension 7 suitably slotted to receive the end of a clamping member 8 pivotally mounted upon the axis 9. This member 8 is movable in a vertical plane toward or from the overhanging arm 5 so as to be readily engaged with the slotted extremity of said arm or disengaged therefrom. A wing-nut 10 threaded upon this member 8 is provided for suitably 95 100

clamping the arm to exert pressure in the manner hereinafter described. Depending from the central portion of the arm 5 is a fixed post 11 to the lower extremity of which is freely swiveled the pressure member 12. This latter element comprises a pair of opposite relatively long arms 12' and a pair of opposite relatively short arms 12'' all of which excepting one of the short arms only 10 are preferably flanged as indicated at 13.

With this clamping means I employ a fuel holding device which also performs the further function of holding the patch or vulcanizable material. Said device consists 15 of a shallow metal pan 14 which is provided with an annular laterally projecting flange 15. The flange referred to performs a dual function in that it acts as a cooling flange permitting the pan to be readily handled 20 when in heated condition and also acting to support said pan when engaged with the flanges 13 of the pressure member 12. As indicated in Fig. 1 the pan is suitably inserted laterally of the member 12. The surface 25 of the bottom of the pan has preferably attached thereto vulcanizing material 16, uncured gum, and at the other side within the pan is provided an inflammable substance 17. This latter may be cardboard 30 impregnated with some inflammable material which will burn without flame preferably, and yet supply sufficient heat for performing the vulcanizing process.

The use of the invention will easily be 35 understood from the foregoing description, it being only necessary to dispose the vehicle tube upon the base 1 with the puncture arranged substantially centrally of said base. The arm 5 is then moved downwardly 40 until the fuel holding member with its vulcanizable material rests upon the punctured portion whereupon the clamping member 8 is engaged with the arm and sufficient pressure exerted against the fuel holding device 45 to obtain the desired result. The fuel substance 17 is then ignited and the process of vulcanization carried out in this manner. The advantage of the swiveling of the member 12 is evident because the fuel holding 50 pan with its patch may be disposed at any angle conforming to the angle of the rupture of the tube and the fact that the holding means is movable with the arm 5 which sustains the same, makes it extremely easy 55 to obtain the exact position of the patch upon the tube.

The foregoing device is designed to be placed within a suitable container with a supply of several fuel holding means with 60 patches and inflammable material arranged thereon, this forming a convenient kit for carrying about with the vehicle for use at any time required. The pan 14 is designed to be of cheap material so that when once 65 used it may be easily discarded and the pro-

tection of the cooling flange 15 enables said pan to be displaced from the member 12 when it has performed its function in the manner above described.

Having thus described my invention, what I claim as new is:

1. In a vulcanizing device of the class described, the combination of a base upon which the part to be vulcanized is disposed, an overhanging arm movably connected to the base at one side, a support depending from the arm, pressure arms mounted on said support, and adjustable with respect to the part to be vulcanized preliminary to application of pressure thereto, a vulcanizing member engageable by said arms, and clamping means at the other side of the base operable to impart clamping action when the operative vulcanizing position has been determined by the arms aforesaid. 85

2. In a vulcanizing device of the class described, the combination of a base, an overhanging arm movably connected to the base, a support depending midway from the arm over the base, a fuel holding pan detachably connected to the support for movement with the arm into vulcanizing position on the part to be vulcanized preliminary to application of pressure thereto, and pressure means pivotally connected to the base 90 for swinging into and out of coöperative engagement with the arm while the latter is in operative position with respect to the part to be vulcanized.

3. In a vulcanizing device of the class described, the combination of a base, an overhanging arm pivotally connected to said base, a clamping member pivotally connected to the base and movable toward or from the arm for engagement or disengagement therefrom, a swivel support depending from the arm, a holding device swiveled to said support and comprising radially extending arms having holding means, and a fuel holding member constructed for detachable connection with said holding means for movement therewith. 105

4. In a vulcanizing device of the class described, the combination of a base, an overhanging arm pivotally connected thereto, clamping means coöperating with said arm for imparting pressure thereto, a rotatable pressure device secured to said arm, and a fuel holding member adapted to co-operate with said pressure device and provided with a cooling flange, said flange constituting means for holding said fuel holding member upon the pressure element aforesaid. 115

5. In a vulcanizing device of the class described, the combination of a base upon which the part to be vulcanized is disposed, an overhanging arm pivotally connected to the base at one side, a support depending from the arm, pressure arms swivelly 120 connected to the support and adjustable with respect to the part to be vulcanized. 125

mounted on said support and adjustable about the axis thereof with respect to the part to be vulcanized preliminary to the application of pressure thereto, a vulcanizing member separate from but engageable by said arms, and clamping means pivotally mounted at the other side of the base and

movable into and out of engagement with the overhanging arm whereby to impart clamping action when the operative vulcanizing position has been determined by the arms aforesaid.

In testimony whereof I affix my signature.

BESHARA I. MALOUF.
